GOODLET M. PALMER AND LEWIS M. PALMER, OF PHILADELPHIA, PENNSYLVANIA,
ASSIGNORS OF THIRTEEN-TWENTIETHS TO GOODLET M. PALMER AND SEVEN-
TWENTIETHS TO LEWIS M. PALMER.

NON-REFILLABLE BOTTLE AND LIKE VESSEL.

1,142,978.

Specification of Letters Patent. Patented June 15, 1915.

Application filed June 30, 1914. Serial No. 848,317.

To all whom it may concern:

Be it known that we, GOODLET M. PALMER and LEWIS M. PALMER, citizens of the United States, residing at Philadelphia, in 5 the county of Philadelphia and State of Pennsylvania, have jointly invented certain new and useful Improvements in Non-Refillable Bottles and like Vessels, of which the following is a specification, the same having 10 particular relation to our pending application for Letters Patent Serial No. 759,719 and filed April 8, 1913.

This invention relates to non-refillable bottles, jugs, jars and similar vessels and has 15 for its principal object to prevent the fraudulent refilling thereof after the same have once been exhausted of their original contents.

A further object of the present invention 20 is to provide means which shall operate for the intended purpose more effectively than means heretofore devised and which at the same time, shall be of such simple construction that the bottles or other vessels may 25 be manufactured without a prohibitive increase in the cost thereof.

A still further object of the present invention resides in the providing of a novel 30 form of valve structure the general details of construction and arrangement of parts of which will hereinafter more fully appear.

With these and other objects in view, the invention consists of the improvements hereinafter described and finally claimed.

35 The nature, characteristic features and scope of the invention will be more fully understood from the following description taken in connection with the accompanying drawings forming part hereof and in which:

40 Figure 1, is a view in central section of the upper portion of a bottle constructed in accordance with the invention, Fig. 2, is a similar view showing the bottle in tilted position and illustrating the manner in which 45 the valve operates to prevent refilling of the bottle in such position, and Figs. 3, 4 and 5, are perspective views illustrating details of construction.

Referring now to the drawings, there is 50 illustrated our new and novel valve embody-

ing the invention and for the sake of illustration, the same is shown as being applied to a bottle. In the practice of the invention, use is made of a glass or other bottle 1, having a neck 2, in which is formed an annular 55 groove 3, located somewhat below the point reached by the ordinary cork 4. Within the neck 2, and at a point considerably below the groove 3, is an annular rim or shoulder 5, forming a stop, the bottom of which 60 is tapered or flared as at 6. The purpose of the flaring portion 6, is to permit of the contents of the bottle finding a ready exit through the port to be presently described. Snugly fitting within the neck of the bottle 65 is a two-part separable casing or cylinder comprising a base forming a valved port and a top forming a guard, which combined casing parts abut against the rim or shoulder 5. The valved port comprises a disk- 70 like cage 7, which is provided with an open- or port 8, extending therethrough and is considerably larger at the bottom than at the top thereof and is shown as being slightly flaring in order that the contents of 75 the bottle may find a ready exit. Extending upwardly from the top of the cage 7, and surrounding the port 8, therein is an annular flanged portion 9, of smaller diameter than the cage, the top of which flanged portion forms a valve seat. The cage 7, is further provided with a depending flange 10, also of smaller diameter than the cage which is adapted to snugly engage the inner surface of the rim 5. Seated upon the cage 7, 80 between the inner walls of the bottle neck and annular flanged portion 9, hereinafter described, is the skirt of the inverted generally cup-shaped guard 11, which closely 85 hugs the inner walls of the bottle-neck. 90 This guard 11, is fully described and claimed in our above mentioned application. Briefly stated, it is provided at its top with a pouring opening 12, and has extended upwardly from its top an annular perforated 95 wall carrying a horizontally disposed plate or disk 13, which is of slightly smaller diameter than is the diameter of the casing parts thus leaving an annular space 14, for the exit of liquid from the bottle. Below 100

the opening 12, the casing parts are tapered toward said opening as at 15. The side walls of the guard are provided with spring detents 16, for engaging the annular groove 3, in the neck 2, of the bottle 1, for interlocking the casing parts together. Thus, when the guard 11, is inserted within the neck of the bottle and is seated upon the cage 7, the detents spring outwardly and engage within the annular groove 3, thus securely locking said parts with respect to the bottle neck to prevent withdrawal therefrom. In practice the flanged portion 9, of the cage 7, has screw-threaded relation as at 17, with the skirt of the guard 11. This is so that when the valve parts about to be described are assembled in proper position, the combined cage and guard may be fitted within the bottle neck without disarranging the valvular parts.

Obviously, in lieu of screw-threaded relation, the cage and guard may be secured together in any appropriate manner. A valvular member 18, preferably of disk formation, is freely seated upon the cage top to normally close the port 8. As shown this valvular member 18, is of a diameter substantially equal to the inner diameter of the skirt of the guard 11, and is preferably provided with a series of spaced openings 19, to permit of the passage therethrough of liquid contained within the bottle. As shown, these spaces 19, are formed by cutting from the peripheral edge of the valvular member, tooth-like projections 20, although, obviously, the spaces 19, may be otherwise formed. The top of the valvular member is preferably flat as at 21, and the underside thereof is slightly cupped out as at 22, to form an annular rim 23, so that the valvular member may more readily seat itself with respect to the cage. In this connection, it is to be noted that the bottoms of the tooth-like projections 20, are free of the cage top, see Fig. 1. Normally disposed by gravity to rest upon the valvular member 18, to cause the same to close the port 8, is a dished semi-spherical member 24. The bottom wall of this member 24, is of a thickness in excess of the member side walls, so that the same is freely tilttable and the tendency thereof is to move toward and maintain an abutting position with the valvular member 18. In other words, except when the bottle is in inverted or pouring position, the member 24 and valvular member are in abutting positions. Of course, when the bottle is in inverted or pouring position, the member 24 drops to the inclined wall 15, of the guard and thus permits the valvular member to leave its seat upon the cage 7. The side walls of the member 24, are provided with liquid pouring ports 25, which, as shown, extend entirely around the member walls.

Obviously, the shape of these ports is immaterial.

In pouring out the contents of the bottle, the same is inverted, thereby causing the member 24 to move away from the valvular member 18, so that the contents of the bottle 70 passing through the port 8, finds its way around the valvular member 18, through the spaces 19, thence through the ports 25, in the member 24, and thence through the opening 12, of the guard.

75

Should attempt be made to refill the bottle by moving the same to a horizontal position or to the position shown in Fig. 2, the member 24, will tilt sufficiently to maintain the valvular member 18, in abutting position 80 with its valve seat.

To fill the bottle originally, it will be understood that the valvular member 18, and member 24, are assembled within the guard 11, and the cage 7, secured with respect to 85 the guard. The bottle being filled, the combined guard and cage are then fitted to place within the bottle neck, the detents of the guard accommodating themselves within the annular groove 3, as hereinbefore described. 90

What we claim is:

1. In a non-refillable bottle having an annular rim in the neck thereof, a cage having a port therethrough seated upon said rim, a guard fitted within the bottle neck for engaging and holding said cage in place upon said rim, an inverted dished disk-valve provided with peripheral pouring spaces, loosely seated upon the cage top and a semi-spherical dished member having continuous 100 side walls provided with liquid pouring ports in its side walls immediately adjacent its top and extended entirely therethrough tiltably mounted upon said disk-valve.

95

2. In a non-refillable bottle having an annular rim in the neck thereof, a cage having a port therethrough seated upon said rim, a guard fitted within the bottle neck for engaging and holding said cage in place upon said rim, an inverted dished disk-valve of a 110 diameter substantially equaling the inner diameter of the guard, loosely seated upon the cage top and provided peripherally with a multiplicity of spaced pouring spaces, and a semi-spherical dished member having continuous side walls the bottom wall of which exceeds in thickness its side walls, tiltably mounted upon said disk-valve the side walls of which member are provided with spaced liquid pouring ports immediately adjacent 120 its top and extended entirely therethrough.

115

3. In a non-refillable bottle, a cage constituting a valve-seat secured in the neck of a bottle, an inverted dished valvular member loosely seated upon said cage, a semi-spherical dished member having continuous side walls provided with liquid ports in its side walls immediately adjacent its top and ex-

125

tended entirely therethrough, tiltably signed our names in the presence of two mounted upon the valvular member and a witnesses.
guard fitted within said bottle for engaging and holding the cage to place and retaining
said valvular member and semi-spherical member in operative position.

In testimony whereof, we have hereunto

GOODLET M. PALMER.
LEWIS M. PALMER.
